UNITED STATES PATENT OFFICE.

RICHARD F. W. LOPER, OF PHILADELPHIA, PENNSYLVANIA.

DESIGN FOR AN ILLUMINATING-CANDLE.

SPECIFICATION forming part of Design No. 12,596, dated December 13, 1881.

Application filed June 1, 1881. Term of patent 7 years.

To all whom it may concern:

Be it known that I, RICHARD F. W. LOPER, a citizen of the United States, residing at the city of Philadelphia, in the State of Pennsylvania, have invented and produced a new and original Design for Illuminating-Candles, of which the following is a specification, reference being had to the accompanying drawings, forming part thereof.

10 Figure 1 is a longitudinal sectional view of my newly-designed candle. Fig. 2 is a horizontal sectional view of the same; and Fig. 3 is a perspective, showing my newly-designed candle in its entirety.

15 Heretofore candles for illuminating purposes have been molded into a cylindrical form. The

design I present shows a departure from this form in a candle molded of an elliptical form in cross-section.

A is the wick, and B the body of the candle, 20 which is molded around the wick in an elliptical form in cross-section.

What I claim as new is—

The design herein shown for illuminating-candles, consisting of a candle elliptical in 25 outline when taken in cross-section, substantially as described.

RICHARD F. W. LOPER.
